[57] CLAIM

The ornamental design for a sled, as shown and described.

DESCRIPTION

FIG. 1 is a top plan view of a sled showing my new design with the lid in open condition;

FIG. 2 is an end elevational view thereof;

FIG. 3 is a perspective view thereof;

FIG. 4 is a bottom plan view thereof, with the lid in closed condition; and

FIG. 5 is an end elevational view thereof opposite to that shown in FIG. 2.

The top of the lid and side of the sled opposite to that shown in FIG. 3 are flat and unornamented.
